Inventor,

John H. Burck
By Frank C. Curtis
Attorney

UNITED STATES PATENT OFFICE.

JOHN H. BURCK, OF ALBANY, NEW YORK.

FRUIT-JAR OPENER.

1,407,632.

Specification of Letters Patent. Patented Feb. 21, 1922.

Application filed June 24, 1919. Serial No. 306,409.

To all whom it may concern:

Be it known that I, JOHN H. BURCK, a citizen of the United States, residing at Albany, in the county of Albany and State of New York, have invented new and useful Improvements in Fruit-Jar Openers, of which the following is a specification.

Reference may be had to the accompanying drawings, and the reference characters 10 marked thereon, which form a part of this specification. Similar characters refer to similar parts in the several figures therein.

This invention relates to means for facilitating the removal of the cover from the 15 body of a common fruit-jar which is ordinarily sealed by a rubber gasket.

Much difficulty is encountered in removing the covers of such jars by reason of the 20 partial vacuum formed within the jar due to the sealing of the jar while its contents are in a heated condition, and the subsequent cooling of the contents.

This difficulty is accentuated by the methods commonly employed in canning fruits 25 and vegetables of boiling the filled covered jars which tends to vulcanize the rubber gasket to the oppositely disposed surfaces of the mouth of the jar and of the cover.

In opening fruit-jars of this kind, it is 30 customary to force the pointed end of a knife, fork or the like into the rubber-filled joint between the top and body of the jar which is not only difficult in many instances, but is also dangerous to the person opening 35 the jar due to the tendency of the inserted point to slip and injure the hand which is holding the jar.

The principal object of the present invention is to facilitate prying the cover from 40 the body of such a jar without danger of injury to the person opening the jar.

Other objects will appear in connection with the following description.

Fig. 1 of the drawings is a view in side elevation of the upper portion of a covered fruit-jar showing my opener applied thereto, and illustrating by dotted lines the movement of the pry of the opener and the resultant opening movement of the jar-cover.

50 Fig. 2 is a view in side elevation of the bar which supports the pry and the pry-resisting member.

Fig. 3 is a view in side elevation of the pry apart from the bar.

55 Fig. 4 is an edge view of the same.

Fig. 5 is a view in perspective of the pry-resisting member.

Fig. 6 is a view in side elevation of a modified form of my opener.

Referring to the drawings wherein the invention is shown in preferred form, 1 represents the body of an ordinary fruit-jar, 2 the removable top of the jar, and 3 the rubber-gasket which seals the joint between the top and body of the jar.

I have shown a type of jar having the usual wire clamping-wire 4, and locking-wire 5.

My improved jar-opener comprises a bar, 6, a pry, 7, and a pry-resisting member, 8. 70 As shown in Fig. 1, the pry comprises a lever pivoted at 9, upon a downwardly offset end, 10, of the bar, 6.

The lower end of the lever, 7, is inwardly offset at 11 and horizontally flattened, terminating in the form of a knife-edge to enter the rubber-sealed joint between the top and the body of the jar.

The upper end, 12, of the lever, 7, forms an operating-handle.

The pry-resisting member, 8, has its upper end in the form of a slide, 14, capable of adjustment longitudinally of the bar, 6, and having its lower end adapted to engage the covered jar on the side opposite that engaged by the pry-end, 11.

The pry-resisting member, 8, may be made to engage any convenient portion of the side of the covered jar opposite that engaged by the pry-end, 11.

I prefer however, to form the pry-resisting member, 8, with a transverse ridge, 13, adapted to engage the rubber-sealed joint of the covered jar on the side opposite that engaged by the pry-end, 11.

In operating the device, the opener is applied to the upper portion of the jar with the wedge-end, 11, withdrawn outwardly as far as possible and placed in engagement with the rubber-sealed joint on one side of the covered jar, and the pry-resisting member, 8, is then slid inwardly along the bar, 6, until its ridge, 13, engages the rubber-sealed joint between the top and the body of the jar on the side opposite that engaged by the wedge-end, 11.

The end of the bar having the pry-resisting member, 8, is then held by one hand while with the other hand the operator forces the handle-end of the pry-lever, 7, out- 110

wardly causing the wedge-end, 11, of said lever to be forced inwardly and then upwardly into the rubber-filled joint between the top and the body of the jar, unsealing 5 and then lifting the edge of the cover on that side of the jar as indicated by dotted lines in Fig. 1.

In the opening operation, the wedge-end, 11, of the pry-lever first acts as a wedge, and 10 then as a lever, its leverage being obtained by its engagement with the neck of the jar which serves as a fulcrum for the lever.

The pry-resisting member, 8, is preferably made adjustable longitudinally of the 15 bar, 6, to adapt the opener for jars of different sizes.

In Fig. 6 I have shown a modified form 20 of my improved jar-opener in which the pry-resisting member, 8^a, is formed by an integral downwardly extended end of the bar, 6^a, and the pry-lever, 7^a, is pivotally mounted at 9^a, upon a slide, 14^a, whereby the pry-lever can be adjusted toward and from the pry-resisting member, 8^a.

25 In this form of the invention, the pry-lever terminates at its lower end in a pry-end,

11^a, and at its upper end in an operating handle, 12^a.

I have shown the members of the opener in each case made of sheet-metal cut and 30 bent to the desired form. I do not wish to be limited however, to this manner of construction, as the members may be made in any desired manner from any suitable material whereby they operate substantially 35 in the manner, and accomplish substantially the functions, above set forth.

What I claim as new and desire to secure by Letters Patent is—

A fruit-jar-opener comprising a bar having 40 means for engaging the opposite sides of a covered jar, one of said means comprising a pry pivoted upon the bar having one end offset horizontally flattened and wedge-shaped to enter between the top and body 45 of the jar, and the other end in the form of an operating handle, one of said means being capable of adjustment longitudinally of the bar.

In testimony whereof, I have hereunto 50 set my hand this 14th day of June, 1919.

JOHN H. BURCK.
